UNITED STATES PATENT OFFICE.

GEORGE CRERAR, OF SPOKANE, WASHINGTON.

MIXING DEVICE.

1,119,405.

Specification of Letters Patent.

Patented Dec. 1, 1914.

Application filed April 8, 1913. Serial No. 759,821.

To all whom it may concern:

Be it known that I, GEORGE CRERAR, a citizen of the United States of America, residing at Spokane, in the county of Spokane and State of Washington, have invented certain new and useful Improvements in Mixing Devices, of which the following is a specification.

This invention pertains to a mixing device and has for its object to provide an improved construction whereby liquids holding particles in suspension may be agitated. For example, for agitating a solution of potassium or sodium cyanid containing particles of pulverized ore, as slime and fine sand.

A further object is to provide a mechanism of the character named that will afford a practical means for adding a gas, liquid or emulsion to a mixture, for instance, for adding hydrated lime to a cyanid solution and carrying the same into the mixture in such a manner that the same may be speedily commingled therewith.

A still further purpose is to construct the mechanism in such a manner that all gearing and bearings are free from contact with the mixture, the object of which will be apparent.

The invention will be hereinafter specifically described and illustrated in the accompanying drawings, in which—

Figure 1, is a vertical sectional view of a tank filled with liquid, with my improved construction shown, Fig. 2, is an enlarged horizontal sectional view taken on the line 2—2 of Fig. 1, and Fig. 3, is an enlarged sectional view of the top of the tubular shaft, the gears attached thereto, a connecting thimble and a broken-away sectional view of a connecting conduit.

Centrally disposed within the tank 10 and vertically arranged is a cylinder 11 having an annular flange 12 at its base, mounted on brackets 13 to provide a space 14 between the base of the cylinder or flange 12 and the bottom 15 of the tank 10. The top of the cylinder 11 is provided with an annular curved flange 16. Brackets 17 reach from the flange 16 to the top wall 18 of the tank 10 serving to support the cylinder 11 and providing a space 19 between the top of the cylinder and the top of the tank for an inflow of the liquid 20 into the cylinder 11. Mounted at the top of the tank 10, vertically arranged and extending through the

top wall 18 of the tank 10 and into the top end of the cylinder 11 is a shaft 21 having a vertical opening 22 through the same. To the bottom of the shaft 21 are attached the angular blades 23. Boxings 24 carrying suitable bearings 25 engage the shaft 21 where it passes through the wall 18 of the tank 10.

Near the top of the shaft 21 and horizontally secured thereto is a gear 26, which meshes with a vertical gear 27 attached to the horizontally arranged shaft 28. Wheels 29 are secured to the shaft 28 which may be connected to a source of power by belts connected therewith. However, any ordinary means for rotating the shaft 21 may be used. The top of the shaft 21 is provided with an annular flange 30 having an internal annular groove 31. A thimble 32 has an external annular flange 33 which engages the groove 31 in the flange 30, the idea being to form a union that will permit of the rotation of the shaft 21 without rotating the thimble 32. Connected with the thimble 32 is conduit 34 leading to a source of gas, liquid or emulsion supply.

The tank 10 is filled with the liquid 20 to a point above the flange 16 at the top of the cylinder 11. The power is applied to the shaft 21, rotating the same to the right. The blades 23 drive the liquid 20 downwardly through the cylinder 11 in the direction of the arrows shown in the cylinder, thence out through the space 14 between the bottom of the cylinder 11 and the bottom 15 of the tank 10. The rarefaction created in the top of the cylinder 11 by the displacement of the blades 23 causes the liquid 20 to flow inwardly over the flange 16 at the top of the cylinder 11, creating a continual movement of the liquid in the direction of the arrows shown in the tank 10 and cylinder 11.

When it is desired to add a new element to the mixture forming the liquid 20, and to speedily and effectively commingle the same with the contents of the tank 10, the same is supplied through the conduit 34 from which it passes through the thimble 32 and the opening 22 in the shaft 21 to a point below the blades 23, where the same receives the downward force of the rotating blades 23 to drive it into rapid contact with the elements already forming the mixture.

What I claim is,

1. A mixing device comprising a tank

with closed bottom and sides, a cylinder having an annular flange at top and bottom vertically arranged and centrally disposed within the tank reaching from a point near the bottom of the tank to a point near the top thereof with an open space between the end thereof and the top and bottom respectively of the tank, a short shaft having blades at its lower end mounted at the top of the cylinder and extending downwardly a short distance only below the top of the cylinder and within the same and means above the liquid area in the tank for rotating the shaft.

15 2. A mixing device comprising a tank with closed bottom and sides, a cylinder having an annular flange at top and bottom vertically arranged and centrally disposed within the tank reaching from a point near 20 the bottom of the tank to a point near the top thereof with an open space between the ends thereof and the top and bottom respectively of the tank, a vertically arranged short shaft with a vertical opening through 25 the same and blades at the bottom thereof mounted at the top of the cylinder and extending downwardly a short distance only

below the top of the cylinder and within the same, a conduit connected with the top of the shaft and means above the liquid area 30 in the tank for rotating the shaft.

3. A mixing device comprising a tank with closed bottom and sides, a cylinder having an annular flange at top and bottom vertically arranged and centrally disposed 35 within the tank reaching from a point near the bottom of the tank to a point near the top thereof with an open space between the ends thereof and the top and bottom respectively of the tank, a vertically arranged 40 short shaft with a vertical opening through the same and blades at the bottom thereof mounted at the top of the cylinder and extending downwardly a short distance only 45 below the top of the cylinder and within the same, a conduit connected with the top of the shaft and means for rotating the shaft.

In testimony whereof I affix my signature in presence of two witnesses.

GEORGE CRERAR.
